US0D1113613S

(12) **United States Design Patent** (10) **Patent No.:** **US D1,113,613 S**
(45) **Date of Patent:** **** Feb. 17, 2026**

(54) **MUFFLER**

(71) Applicant: **Indian Motorcycle International, LLC**, Medina, MN (US)

(72) Inventors: **Bartłomiej Krawczykowski**, Opole (PL); **Lucas Torres**, Wyoming, MN (US); **Ola Ingvar Stenegard**, Burgdorf (CH); **Akshay A. Biyani**, Wyoming, MN (US); **Brian N. Flick**, Medina, MN (US); **Michael Philpott**, Rolle (CH)

(73) Assignee: **INDIAN MOTORCYCLE INTERNATIONAL, LLC**, Medina, MN (US)

(**) Term: **15 Years**

(21) Appl. No.: **29/943,768**

(22) Filed: **May 23, 2024**

Related U.S. Application Data

(62) Division of application No. 29/828,835, filed on Mar. 1, 2022, now Pat. No. Des. 1,039,458.

(57) **CLAIM**

The ornamental design for the muffler as shown and described.

DESCRIPTION

FIG. 1 is a right front perspective view showing the new design for a muffler;

FIG. 2 is a front view of the muffler of FIG. 1;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The portions of the muffler shown in broken lines form no part of the claimed design.

1 Claim, 6 Drawing Sheets
